UNITED STATES PATENT OFFICE.

JOSEPH SYLVAN, OF CICERO, ILLINOIS.

WINDOW CONSTRUCTION.

Application filed May 5, 1922. Serial No. 558,595.

To all whom it may concern:

Be it known that I, JOSEPH SYLVAN, a citizen of the United States, and a resident of Cicero, in the county of Cook and State of Illinois, have invented certain new and useful Improvements in Window Constructions; and I do hereby declare that the following is a full, clear, and exact description thereof, reference being had to the accompanying drawings, and to the letters of reference marked thereon, which form a part of this specification.

This invention relates to improvements in window construction and consists of the matters hereinafter described and more particularly pointed out in the appended claims:

One of the objects of the present invention is to improve the construction and operation of that kind of window, wherein the sash is not only capable of a vertical sliding movement in the frame but is also capable of an inward swinging movement with respect thereto.

A further object of the invention is to provide novel means for locking the sash against a vertical sliding movement after it has been swung inwardly about the bottom end as a pivot.

The advantages of the invention will more fully appear as I proceed with my specification.

In the drawings:—

Figure 1 is a view in elevation of a window construction embodying my invention, as viewed from the inside of a room.

Figure 2 is a vertical section in the line 2—2 of Fig. 1, the window sash being shown in side elevation.

Figure 3 is a horizontal section—through the improved window construction, on an enlarged scale, as taken on the line 3—3 of Fig. 1.

Figure 4 is a central vertical sectional view, as taken on the line 4—4 of Fig. 1.

Figure 5 is an enlarged view of the parts shown at the bottom end of Fig. 4, with the window sash swung inwardly into one of its open positions.

Figure 6 is a view similar to Fig. 5 with the window sash in a position different from that shown in Fig. 5.

Figure 7 is a detail horizontal sectional view on an enlarged scale as taken on the line 7—7 of Fig. 1.

Figure 8 is a view similar to Fig. 7 with the parts in a changed relation.

Figure 9 is a vertical detail sectional view as taken on the line 9—9 of Fig. 7.

Figure 10 is a view similar to Fig. 9 with the parts in a changed relation. 60

Figure 11 is a perspective view of a braking block embodied in my improved window construction.

Figure 12 is a perspective view of a sash bracket plate embodied in my improved 65 window construction which will be more fully referred to later.

Referring now in detail to that embodiment of the invention illustrated in the accompanying drawings, 15 indicates as a 70 whole, a window frame and 16 and 17 indicate the top and bottom sash associated therewith. The window frame includes upright side members 18, a top lintel 19 and a sill 20, all of well known construction. Fixed to 75 the opposed faces of the side members are the inner and outer moulding strips 21—22 which are spaced equidistant apart from the parting strip 23 to provide inner and outer sash grooves 24—25 respectively, for the bottom and top sash 17 and 16. 26—26 indicate sheet metal channel strips which fit snugly in and extend the full length of the outer sash grooves 25. Said channel strips each include outer and inner flanges 27—28 85 which engage in grooves 16^a—17^a in the outer surfaces of the upright side members, 16^b and 17^b of the top and bottom sash 16 and 17. (See Fig. 3.)

The side members 16^b—17^b of the sash 90 carry threaded bushings 30—31 to receive cooperating locking pins 32—33 which may be threaded through said bushings to engage the side members of the frame, to lock the sash against both a vertical sliding and an 95 inward swinging movement as will later appear. In the case of the pins 32 associated with the top sash, the channel strips 26 are provided with suitable holes or apertures through which said pins extend to engage 100 the side members, as shown in Fig. 3.

In the moulding strips 21 I provide short ratchet plates 21^a with which the pins 33 coact to hold the sash 17 in a slightly tipped or swung inward position. 105

Secured to the bottom of each sash are plates 34 (see Fig. 12) each of which carries a laterally projecting tongue extension 35. Each tongue extension is elliptical in cross section with its major axis arranged vertically, and the extreme end of said tongue is bevelled off as at 35^a. The tongue 35 of

each plate normally extends into a recess 36 in an associated block 37 (see Fig. 11) located in each of the frame grooves 24-25, there being a pair of such blocks for each sash 16 and 17. In the case of the pair of blocks associated with the top sash, they are arranged, one within each channel 26. The recess 36 in each block opens through one edge thereof and includes a bevelled end 10 wall or surface 38 which co-acts with the bevelled end 35^a of the tongue 35, as will later appear. In each block is provided a vertically disposed opening 39 to receive the knotted end of a sash cord 40, the cords 15 passing over the usual pulleys 41 in the top ends of the side frame members, to be secured to the associated window weights in the usual manner. (See Fig. 4.)

When the sash is in its normally upright 20 closed position the major axis of each tongue 35 extends vertically in the associated recess 36 so that the blocks are free to slide in the frame grooves with the sash (see Figs. 7 and 9) when the lower sash is swung inwardly about said tongue as pivots, the engagement of the tongues in said recesses will not only force said blocks against the parting strips 23 but will, on account of the co-acting bevelled surfaces 35^a and 38 force 25 said blocks laterally outward so that they will frictionally engage with the adjacent parts of the frame and lock said sash against vertical movement after it has been swung inwardly. In the case of the blocks associated with the top sash 16, said blocks are moved to engage parts of the channel strips 26 in a like manner. Thus no matter in 30 what vertical position either sash may be in, when it is swung inwardly it is automatically locked against further vertical sliding movement in the frame in either direction.

In addition to the automatic locking means just described, I may also employ in 45 connection with the lower sash 17, another locking means which is brought into operation when said bottom sash is in its substantially lowest position in the frame. Such means is as follows: To the side members of 50 the frame, just inward of the moulding, strips 21 and near the sill 20, I secure plates 42 each of which includes a lateral hook extension 43. Fixed to the inner face of the sash members 17^b near the bottom, are plates 55 44, each of which includes an inwardly projecting bottom hook 45 and an inwardly projecting top lug 46. When it is desired to swing the bottom sash inwardly beyond that position in which it can be locked by 60 the pins 33 and toothed plates 21^a, said pins are first withdrawn and the sash is then swung inwardly until the lugs 46 engage beneath the ends of the hooks 43 on the frame plates 42. When the sash is in 65 this position, as shown in Fig. 5, the en-

gagement of the lugs 46 and hooks 43 will prevent any further upward or raising movement of the sash. When it is desired to swing the sash into its full open position, say for the purpose of washing the 70 outside thereof, it is pushed outwardly to disengage the hooks 43 and lugs 46 and then raised a short distance, after which it is swung inwardly until the hooks 45 engage the ends of the hooks 43 and the lugs 75 46 engage the top of said hooks 43, as shown in Fig. 6. The sash is now locked in a position convenient for cleaning the outside of the same. To facilitate the inward and outward swinging movement of the bottom sash, I provide a handle 47 at the top end 80 thereof.

By reason of the engagement of the flanges 27-28 of the channel strips 26, in 85 the grooves 16^a and 17^a of the sash, said channel may shift laterally, in or out of its associated frame groove to accommodate itself to any contraction or expansion of the sash and thus a weather tight connection is 90 provided between the frame and sash at all times.

While, in describing my invention, I have referred to certain details of mechanical construction and arrangement of parts, I do not wish to be limited thereto except as may 95 be pointed out in the appended claims.

I claim as my invention:

1. In combination with a window frame and a sash which is capable of either a vertical sliding movement or an inward swinging movement about a horizontal axis with respect to said frame, means providing a sliding guiding bearing for the sash in the frame, and coacting hook members on the sash and frame respectively adapted for engagement with each other when the sash has been swung inwardly, to lock said sash against vertical movement with respect to the frame.

2. In combination with a window frame and a sash which is capable of either a vertical sliding movement or an inward swinging movement with respect to said frame, means providing a sliding guiding bearing for the sash in the frame including a part pivoted to the sash and adapted for engagement with a fixed part of the frame, and coacting hook members on the sash and frame respectively adapted for engagement with each other when said sash has been swung inwardly, to limit the inward swing of said sash and also to lock said sash against vertical movement with respect to the frame.

3. In combination with a window frame and a sash which is capable of either a vertical sliding movement or an inward swinging movement with respect to said frame, means providing a sliding guiding bearing for the sash in the frame including a part

pivoted to the sash and adapted for engagement with a fixed part of the frame, and coacting hook members on the sash and frame respectively, adapted for engagement to lock the sash against vertical movement in the frame when said sash has been swung inward into one position, and to lock the sash after it has been swung further inward into a second position, against both a vertical sliding movement in the frame and a further inward swinging movement.

4. In combination with a window frame having grooves in its side members, and a sash which is capable of either a vertical sliding movement or an inward swinging movement with respect to said frame, a block in each frame groove, window cords fixed to the said blocks, and plates fixed to the sash, said plates and blocks having a tongue and recess connection, which in the inward swinging movement of the sash acts to force the blocks into frictional engagement with the walls of the associated groove to lock the sash against a vertical movement

25 in the frame.

5. In combination with a window frame having grooves in the side members, and a sash which is capable of either a vertical sliding movement or an inward swinging movement with respect to said frame, a recessed block in each sash groove window cords connected to the said blocks, plates fixed to the sash, said plates having tongue

extensions which project into the recesses of said blocks, said tongue extensions acting when the sash is swung inwardly, to shift the blocks in a direction at right angles to the sash cords, to frictionally engage the walls of the frame grooves and lock the sash against a vertical movement in the frame.

6. In a window construction, the combination of a window cord block adapted for movement in a window frame groove, said block having a recess therein, a tongue extension adapted to be carried by the sash, said tongue extension normally engaging in said recess, said extension being of such shape that when the sash is swung inwardly into an open position the block is shifted into engagement with the window frame to lock the sash when open against vertical movement in the frame.

7. In combination with a window frame having side members provided with inner and outer sash grooves, top and bottom window sash, slideable in said grooves and each having a groove in the outer surface of its side members, channel strips each having a flange which enters into a respective groove in the outer surface of the side members of both window sash.

In testimony that I claim the foregoing as my invention, I affix my signature this 29th day of April, A. D. 1922.

JOSEPH SYLVAN.
